(57)

CLAIM

The ornamental design for an angled trainline support casting, as shown and described.

DESCRIPTION

FIG. 1 is a perspective view thereof;
FIG. 2 is a side elevation view thereof;
FIG. 3 is a side elevation view thereof;
FIG. 4 is a front elevation view;
FIG. 5 is a rear elevation view;
FIG. 6 is a top view thereof; and,
FIG. 7 is a bottom view thereof.
